FRAME

Filed Nov. 16, 1931

UNITED STATES PATENT OFFICE

HENRY G. MUTSCHLER, OF ROCHESTER, NEW YORK

FRAME

Application filed November 16, 1931. Serial No. 575,291.

This invention relates to frames for interchangeable signs and has for its object to provide such a frame with means which permit signs to be quickly and easily inserted into the frame and removed from it without disturbing the position of the frame.

Another object of this invention is to provide a frame for advertising machines which is rigid, strong and rugged in construction and will retain its shape indefinitely during all climatic changes.

These and other objects of this invention will become more readily apparent from the detailed description which follows, reference being had to the accompanying drawing in which

Figure 1 is a perspective view of the frame.

Figure 2 is a vertical sectional view of the frame, the section being taken on the line 2x—2x of Figure 1.

Figure 3 is a horizontal sectional view of the frame, the section being taken on the line 3x—3x of Figure 1.

Figure 4 is a detail perspective view of a portion of the corner of the frame and one of the locking members with which the corners are fastened together.

Figure 5 is a side elevation of two of the corners of the frame in a position ready to be brought together.

In the several figures of the drawing like reference numerals indicate like parts.

The frame forming the subject matter of my present invention is especially adapted for use in advertising machines such as is illustrated in my application Serial No. 547,664 filed June 29, 1931. In this advertising machine the signs are integral with the frame which surrounds them and in order to change the signs it is necessary to withdraw from the machine the signs with their frames and replace them with others. Furthermore the frames for the signs used in this and similar machines have heretofore been constructed from wood which, when subjected to climatic changes, warped, especially in the larger frames and interferred with the proper continuous operation of the advertising machine.

My present frame is formed up of sheet

metal in such a manner that it forms a rigid, strong and rugged support for the signs which cannot warp and get out of shape. As illustrated in the several figures of the drawing, the frame is formed up of the two side members 1 and 2 and the top and bottom members 3 and 4 respectively. Each of these members is formed up from sheet material in the form of a pair of parallel channels 5 and 6, each having an overhanging flange 7 overhanging part of the open top of the channel on the outside thereof. The two parallel channels 5 and 6 have formed between them an inverted channel 8 which provides a combined stiffening rib and flange for the middle of each of the members making up the frame. This flange thus extends around the inside diameter of the frame and provides the backing against which the signs 10 are held in place as will hereinafter be described.

The ends of the members making up the frame are angular and when brought together form a miter joint between them.

Each of these miter joints is locked together by a pair of angle brackets 11, 11, one-half of each of which is inserted into the channels 5 of one frame member and the other half into the channel 6 of the next frame member. In the same way the second bracket is inserted into the channel 6 of these same frame members. The frame members are thus held in a rectangular position with relation to each other and in order to lock them together in this position each of the locking brackets 11 has one or more holes 12, 12 provided in the side thereof so that the sides of the frame members may be indented at these holes to have the inwardly projecting lugs formed by these indentations engage into the holes 12, 12 and thus lock the locking brackets to the frame members and tie the frame members together.

The sign proper is removably held in place by means of the wire locking member 13. This member is bent up in the form of an open rectangular loop having its ends bent outwardly and pivoted at opposite points in the overhanging flange 7 of the two side members 1 and 2 of the frame. In this way the locking member is adapted to swing in

and out of the inside of the frame as illustrated in dotted lines in Figure 2. The sign proper is made up of suitable sheet material such as cardboard, sheet metal, etc. and when 5 inserted its bottom edge is slipped behind the hinged portion of the wire locking member 13 and placed into the channel 5 or 6 of the bottom frame member between the overhanging flange 7 thereof and the flange 8 as 10 illustrated in Figure 2. After the bottom of the sign is thus located, the remainder of the sign is swung into the frame against the flange 8 of the side and top frame members and the wire locking member is swung in 15 front of it to hold it in place in the frame against these flanges.

The wire locking member is provided with the outwardly projecting lugs 14, 14, one intermediate of each side of the member and 20 another intermediate of the top thereof. These lugs are adapted to engage into depressions 15 formed in the overhanging flanges 7 of the frame members as illustrated in Figures 2 and 3. The fact that the sides 25 and top of the wire locking member will yield, allows the lugs 14, 14 to spring in and out of the depressions 15 when the wire locking member is either forced into or pulled out of the frame. However, while the locking member is in the frame, it securely holds 30 the sign in place in the frame.

I claim:

1. A frame for removable signs comprising top, bottom and side rails, a channel 35 formed in said bottom rail, a locking member pivoted on the inside of said side rails and said top rail and yielding means carried by said locking member adapted to engage said side rails to lock a sign supported in said 40 channel of said bottom rail into said frame.
2. A metal frame for signs comprising top, bottom and side rails each formed up from sheet metal into two parallel channels with a flange formed between said channels and 45 extending above said channels, a miter joint between adjacent rails and angular locking members extending from each of the channels in one rail to the corresponding channels in the adjacent rail.
3. A metal frame for signs comprising top, bottom and side rails each formed up from sheet metal into two parallel channels with a flange formed between said channels and extending above said channels, a miter joint 55 between adjacent rails, angular locking members extending from each of the channels in one rail to the corresponding channels in the adjacent rail and locking means for locking said rails to said locking members.
4. A metal frame for removable signs comprising top, bottom and side rails each bent 60 up from sheet metal and comprising a pair of parallel channels with a flange separating the channels and projecting above the channels, an overhanging flange partially over-

hanging the outside of each of the channels, an inverted U-shaped locking member pivoted in the overhanging flange of two opposing rails and adapted to swing in and out of 70 said frame.

5. A metal frame for removable signs comprising top, bottom and side rails each bent up from sheet metal and comprising a pair of parallel channels with a flange separating the channels and projecting above the channels, an overhanging flange partially overhanging the outside of each of the channels, an inverted U-shaped locking member pivoted in the overhanging flange of two opposing rails and adapted to swing in and out of said frame, a lug formed in said swinging locking member and projecting outwardly thereof, one of 75 said overhanging flanges having a depression therein adapted to receive said lug of said locking member to hold said locking member 80 in place within said frame.
